UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

INKING MECHANISM FOR ROTARY PRINTING-MACHINES.

1,284,213.

Specification of Letters Patent. Patented Nov. 12, 1918.

Application filed January 11, 1915. Serial No. 1,612.

To all whom it may concern:

Be it known that I, HOWARD M. BARBER, a citizen of the United States, and resident of Stonington, in the county of New London and State of Connecticut, have invented a new and useful Improvement in Inking Mechanism for Rotary Printing-Machines, of which the following is a specification.

In inking mechanism for rotary printing machines where the several composition rollers of the mechanism are left in contact with one another and with the cylinders when idle, there is a tendency on the part of the rollers, because of their stationary contact, to become flattened or distorted and thereby destroying their usefulness.

Furthermore, because of their contact, it consumes a considerable period of time to thoroughly clean the rollers.

This invention includes means whereby the several composition rollers may be moved into and out of contact with their coating rollers and cylinders, with the objects in view of leaving the rollers out of contact when standing idle, to prevent the flattening or distortion thereof above referred to; to permit the thorough and independent cleaning of the rollers while out of contact without removing them from the machine; and to facilitate the removal or replacement of any one of the rollers.

This invention also includes more specifically a single means for moving the form rollers into and out of contact with their vibrating rollers; a single means for moving the carrying rollers into and out of contact with their ink cylinders and vibrating rollers; and a single means for moving the distributing rollers into and out of contact with their ink cylinders; the set of form rollers and the set of distributing rollers being mounted in auxiliary frames hinged to the roller frame, the carrying rollers being mounted in movable bearings carried by the roller frame, and the ink cylinders and vibrating rollers being mounted in fixed bearings in the roller frame. Means are also provided for removably securing the roller frame to the main frame and a common means is provided for simultaneously moving the roller frame and the form cylinder in the same direction, whereby the form cylinder may be kept in contact with its form rollers as the roller frame is moved away from the main frame.

A practical embodiment of my invention is represented in the accompanying drawings, in which—

Figure 1 represents so much of an inking mechanism for rotary printing machines as includes my invention, looking at one side of the machine, 60

Fig. 2 is a section taken from front to rear through the machine just inside of the farther side frame, the several rollers and cylinders being shown in their operative contacting positions in dotted outline, 65

Fig. 3 is a diagrammatic section taken from front to rear just inside the near side frame, the several rollers and cylinders being shown thrown out of contact, 70

Fig. 4 is an enlarged detail section showing the means for moving each of the carrying rollers into and out of operative position, and 75

Fig. 5 is a view similar to Fig. 1, looking at the other side of the machine.

The main frame is denoted by 1 and the roller frame by 2. The roller frame is removably secured to the main frame by throw-off locks at each side of the frame, each of which throw-off locks comprises a squared head 3 having a screw threaded shank 4 and a laterally swinging bolt 5 hinged to said head 3 and arranged to enter a recess 6 in a lateral lug 7 projecting from the roller frame, said bolt 5 being provided with a nut 8 arranged to engage the back face of the lug 7 when the bolt is in its locking position, 85

The form cylinder 9 has its shaft 10 mounted in bearings 11 movable to the front and rear in the box 12.

A common means is employed for simultaneously moving the roller frame and the form cylinder in the same direction, which common means is constructed, arranged and operated as follows:

The screw threaded shank 4 of each of the throw-off locks is provided with a worm gear nut 13 which is held against movement on the said screw threaded shank in a bracket 14, which nut meshes with a worm 15 fast on a stud-shaft 16. Each of the bearings 11 for the form cylinder shaft 10 is provided with a screw threaded shank 17 on which is mounted a worm gear nut 18 in a suitable bracket 19 against movement along said screw threaded shank 17. This nut 18 meshes with a worm 20 fast 110

on a stud-shaft 21. A train of gears 22, 23, 24, 25, on each side of the machine connect each pair of stud shafts 21 and 16. A crank handle 26 is fast on the cross shaft 27 which has fast thereon each of the gears 24 of the two trains of gears so that when the crank handle 26 is turned, the bearings for the form cylinder and the throw-off locks will be moved in the same direction 10 thus keeping the form cylinder and its form rollers in contact as the roller frame is moved away from the main frame.

The usual rack and pinion mechanism is provided for moving the roller frame away 15 from the main frame to permit the form rollers to be moved away from the form cylinder so that the form rollers may be moved away from their vibrating rollers; it being understood that the throw-off locks are first 20 released by disengaging their swinging bolts from the roller frame.

The ink fountain is denoted by 28 and its fountain roll by 29, the shaft 30 of which is mounted in suitable bearings 31.

Two ink cylinders 32, 33, have their shafts 34, 35, mounted in fixed bearings in the roller frame 2.

Four vibrating rollers 36, 37, 38, 39, have their shafts 40, 41, 42, 43, suitably mounted 30 in the roller frame, the means for vibrating these rollers not being shown or described herein as it forms no part of the present invention, which means may be of well known or approved construction.

Four ink carrying rollers 44, 45, 46, 47, are shown, the carrying roller, 44, being arranged to be brought into and out of contact with the vibrating rollers 36 and 37, the carrying roller 45 being arranged to be 40 brought into and out of contact with the vibrating roller 37 and ink cylinder 32; the carrying roller 46 being arranged to be brought into and out of contact with the vibrating roller 38 and ink cylinder 32; and 45 the carrying roller 47 being arranged to be brought into and out of contact with the vibrating roller 39 and ink cylinder 33.

A common means is provided for simultaneously moving these carrying rollers, 50 which means is constructed, arranged and operated as follows: The shafts 48, 49, 50, 51, of these carrying rollers are mounted in suitable pairs of bearings 52, 53, 54, 55, having screw threaded shanks 56, 57, 58, 59, 55 adjustably held by worm gear nuts 60, 61, 62, 63, in sockets 64, 65, 66, 67, secured to the roller frame. Pairs of worms 68, 69, 70, 71, mesh with the pairs of worm gear nuts 60, 61, 62, 63, and are fast upon cross 60 shafts 72, 73, 74, 75, which are mounted in the pairs of sockets 64, 65, 66, 67. At one side of the roller frame, the cross shafts 72, 73, 74, 75, are connected by sprocket chains 76, 77, and their respective sprockets 78, 79, 65 80, 81, 82. A crank handle 74* is fast on the

cross shaft 74. As this handle is turned, the bearings for the shafts of the several carrying rollers will be moved inwardly or outwardly together by reason of the worm gear connection between the cross shafts hereinabove referred to and the screw threaded shanks of the said bearings. This forms a rapid means for accomplishing this result. 70

The usual ductor roller 83 is mounted in suitable rocking bearings 84 carried by the 75 cross shaft 85.

The group of distributing rollers 86, 87, 88, 89, 90, have their shafts 91, 92, 92*, 93, 94, mounted in pairs of adjustable bearings 95, 96, 97, 98, 99, in the hangers 100 of an auxiliary frame, which frame is hinged to the roller frame at 101. A cross brace 102 of the roller frame passes through elongated slots 103 in the hangers 100 for guiding the auxiliary frame in its swinging movements. 80 Means are provided for swinging this auxiliary frame to bring the distributing rollers into and out of contact with their ink cylinders, which means comprises a cross shaft 104 mounted in suitable bearings in 90 the roller frame provided with eccentric portions 105 located in elongated slots 106 in the free ends of the hangers 100. This cross shaft 104 at one side of the machine is provided with a suitable crank handle 107. 95

The form rollers 108, 109, 110, 111, 112, 113, have their shafts 114, 115, 116, 117, 118, 119, mounted in suitable adjustable bearings 120, 121, 122, 123, 124, 125, carried by the pair of hangers 126 of an auxiliary frame hinged at 127 to the roller frame. 100

The means which are employed for swinging this auxiliary frame to move the form rollers into and out of contact with their vibrating rollers 36, 38, 39, is constructed, arranged and operated as follows: A cross shaft 128 is mounted in suitable bearings in the roller frame, which cross shaft is provided with a pair of crank arms 129 connected to the free ends of the hangers 126 of the auxiliary frame by links 130. The shaft 128 is provided with arms 131 arranged to engage projections 132 on the links 130 for limiting the movement of the auxiliary frame away from the vibrating rollers. This cross shaft 128 is provided with a suitable crank handle 133 at one side of the machine for swinging the auxiliary frame. 110

A train of gears 134, 135, 136, 137, 138, 139, 140, 141, 142, 143, 144, 145, 146, 147, serves to connect the form cylinder with the several vibrating rollers and ink cylinders. The cam shaft 148 for controlling the movements of the ductor roller is driven through 125 the gears 149, 150.

From the above description, it will be seen that a common means is provided for moving the carrying rollers into and out of 130

contact with both the ink cylinders and their vibrating rollers; a single means is provided for moving the distributing rollers into and out of contact with their ink cylinders and 5 that a single means is provided for moving the form rollers into and out of contact with their vibrating rollers.

While I have shown two ink cylinders and one arrangement of form, vibrating, carrying and distributing rollers, it is evident that 10 my invention is not limited to any particular number of cylinders or rollers or any particular arrangement thereof; hence, I do not wish to limit myself strictly to the structure herein shown and described, but 15

What I claim is:—

1. An inking mechanism for rotary printing machines, including a roller frame, an ink cylinder, ink distributing rollers, carrying rollers, means for simultaneously moving the distributing rollers into and out of contact with the ink cylinder, and independent means for simultaneously moving the carrying rollers into and out of contact with the ink cylinder. 20

2. An inking mechanism for rotary printing machines, including a roller frame, ink cylinders, ink distributing rollers, carrying rollers, means for simultaneously moving the distributing rollers into and out of contact with the ink cylinders, and independent means for simultaneously moving the carrying rollers into and out of contact with the ink cylinders. 30

3. An inking mechanism for rotary printing machines, including a roller frame, an ink cylinder, ink distributing rollers and their auxiliary frame, carrying rollers, means for moving the auxiliary frame to bring the distributing rollers into and out of contact with the ink cylinder, and independent means for simultaneously moving the carrying rollers into and out of contact with the ink cylinder. 40

4. An inking mechanism for rotary printing machines, including a roller frame, ink cylinders, ink distributing rollers and their auxiliary frame, carrying rollers, means for moving the auxiliary frame to bring the distributing rollers into and out of contact with the ink cylinders, and independent means for simultaneously moving the carrying rollers into and out of contact with the ink cylinders. 50

5. An inking mechanism for rotary printing machines, including a form cylinder, its frame, a roller frame, vibrating rollers mounted therein, form rollers, means for moving the roller frame to bring the form rollers into and out of contact with the form cylinder, and independent means for simultaneously moving the form rollers into and out of contact with the vibrating rollers. 60

6. An inking mechanism for rotary printing machines, including a form cylinder, its

frame, a roller frame, vibrating rollers mounted therein, an auxiliary frame, form rollers mounted therein, means for moving the roller frame to bring the form rollers into and out of contact with the form cylinder, and independent means for moving the auxiliary frame to bring the form rollers into and out of contact with the vibrating rollers. 70

7. An inking mechanism for rotary printing machines, including a roller frame, an ink cylinder, vibrating rollers, carrying rollers, ink distributing rollers, means for simultaneously moving the carrying rollers into and out of contact with the ink cylinder and vibrating rollers, and independent means for simultaneously moving the distributing rollers into and out of contact with the ink cylinder. 80

8. An inking mechanism for rotary printing machines, including a roller frame, an ink cylinder, vibrating rollers, carrying rollers, ink distributing rollers and their auxiliary frame, means for simultaneously moving the carrying rollers into and out of contact with the ink cylinder and vibrating rollers, and independent means for moving the auxiliary frame to bring the distributing rollers into and out of contact with the ink cylinder. 90

9. An inking mechanism for rotary printing machines, including a roller frame, ink cylinders, vibrating rollers, carrying rollers, ink distributing rollers, means for simultaneously moving the carrying rollers into and out of contact with the ink cylinders and vibrating rollers, and independent means for simultaneously moving the distributing rollers into and out of contact with the ink cylinders. 100

10. An inking mechanism for rotary printing machines, including a roller frame, ink cylinders, vibrating rollers, carrying rollers, ink distributing rollers and their auxiliary frame, means for simultaneously moving the carrying rollers into and out of contact with the ink cylinders and vibrating rollers, and means for moving the auxiliary frame to bring the distributing rollers into and out of contact with the ink cylinders. 110

11. An inking mechanism for rotary printing machines, including a form cylinder and its frame, a roller frame, form rollers, vibrating rollers, carrying rollers, means for moving the roller frame to bring the form rollers into and out of contact with the form cylinder, means for simultaneously moving the form rollers into and out of contact with the vibrating rollers, and means for simultaneously moving the carrying rollers into and out of contact with the vibrating rollers. 120

12. An inking mechanism for rotary printing machines, including a form cylinder and its frame, a roller frame, form rollers and their auxiliary frame, vibrating rollers, car-

- ing machines, including a form cylinder, its frame, a roller frame, form rollers and their auxiliary frame, an ink cylinder, ink distributing rollers and their auxiliary frame, 30
5 vibrating rollers, carrying rollers, means for moving the roller frame to bring the form rollers into and out of contact with the form cylinder, means for moving the auxiliary form roller frame to bring the form rollers 35
10 into and out of contact with the vibrating rollers, means for moving the auxiliary distributing roller frame to bring the distributing rollers into and out of contact with the ink cylinder, and means for simultaneously 40
15 moving the carrying rollers into and out of contact with both the ink cylinder and vibrating rollers. 45
20 23. An inking mechanism for rotary printing machines, including a form cylinder, its frame, a roller frame, form rollers, ink cylinders, ink distributing rollers, vibrating rollers, carrying rollers, means for moving the roller frame to bring the form rollers into and out of contact with the form cylinder, means for simultaneously moving the carrying rollers into and out of contact with both the ink cylinders and vibrating rollers. 50
25

In testimony that I claim the foregoing as my invention, I have signed my name in presence of two witnesses, this eighth day of January, 1915.

HOWARD M. BARBER.

Witnesses:

F. GEORGE BARRY,
